GAME BOARD

Harold Raoul Wainerdi, New York, N. Y.

Application June 29, 1955, Serial No. 36,759

Term of patent 14 years

(Cl. D34—5)

The figure is a plan view of a game board showing my design.

The game board is of conventional thickness.

The segments of the design of the track bearing the numerals 2 to 20 (in broken lines) are each similarly composed of four panels, each panel being shaded in the same sequence as the first illustrated numeral bearing panel. The dominant features reside in that portion shown in full lines.

I claim:

The ornamental design for a game board, as shown and described.
